UNITED STATES PATENT OFFICE.

JOHN B. POWELL, OF PHILADELPHIA, PENNSYLVANIA, ASSIGNOR TO THE POWELL MOTOR COMPANY, (LIMITED,) OF SAME PLACE.

SPRING-MOTOR.

SPECIFICATION forming part of Letters Patent No. 293,193, dated February 5, 1884.

Application filed October 31, 1883. (No model.)

To all whom it may concern:

Be it known that I, JOHN B. POWELL, a citizen of the United States, residing at the city of Philadelphia, in the county of Philadelphia and State of Pennsylvania, have invented certain new and useful Improvements in Spring-Motors; and I do hereby declare the following to be a full, clear, and exact description of the invention, reference being had to the accompanying drawings, which form part of this specification, in which—

Figure 1 is a vertical section of my improvements, and Fig. 2 a plan view of the lower barrel.

15 My invention has relation to spring-motors of that class in which two or more barrels, each with its own spring, are employed, each barrel being connected to its shaft by its spring, and the barrel of one shaft being 20 coupled to the shaft of the adjoining barrel, so as to rotate therewith; and my improvements relate to the following features of construction: first, to forming or providing the lower barrel with teeth, so as to constitute it, 25 in effect, a gear-wheel, to which the winding-power is applied, thereby dispensing with one gear-wheel in the construction heretofore practiced, and permitting the motor to be wound up while running and without interfering 30 with its running; second, to the provision of an automatic clutch for preventing the unwinding of the motor in case of failure of action of the pawls employed for that purpose.

In carrying my invention into effect I construct the motor generally in accordance with the construction shown and described in Letters Patent of the United States heretofore granted to me, Nos. 219,015 and 246,197, and as shown in the drawings, where A is the 35 base, and B B' two barrels, each with its own shaft and spring connected, as called for by said patents. Instead, however, of employing the gear-wheel shown in said first-recited patent, and which is located near the top of the 40 motor and above the barrels, and which is the wheel whereby, through the intervention of a miter-pinion, the motor is wound up, I form the lower barrel, as shown at B², with gear-teeth b. This makes a gear-wheel as 45 well as a barrel of said lower barrel, B'. I also provide a pinion, C, which gears with

said barrel-wheel B², and is fast on a vertical shaft, e, having bearings in the base A of the motor and in a bracket, D, which is attached to or forms a part of the upper frame-piece, F. By applying a crank or equivalent device to shaft e at its upper end, the pinion C and barrel-wheel B² will be rotated, and the motor thus wound up. As the winding starts on the lower barrel and the power of the 55 springs is given off from the top barrel to the machinery to be operated by the motor, it follows that the motor may, by reason of the construction described, be wound up while running and without interfering with or suspending its action; and as the lower barrel forms also a gear-wheel as well as a barrel, the winding-wheel heretofore employed is dispensed with, thus effecting a saving in cost of construction and reducing the weight of the 60 motor.

Referring now to the second feature of my invention, G G are spring-pawls usually provided to hold the winding-wheel in check, and which in this case are applied to the barrel-wheel B². To avoid unwinding or other accident in case of failure of action of these pawls, I provide an automatic clutch, (shown at H.) This consists of a pawl or wedge, h, which is not pivoted, but is located inside of a cam 75 guard or shield, h', secured to the base A. The point of said pawl or wedge contacts with the teeth of the wheel B² as said teeth pass it in winding, yielding readily, though pressed toward said teeth by a spring, h''. Should the 80 pawls G G fail to act and the wheel B² begin a backward motion, the point of the wedge h will instantly engage with the tooth in advance of it. The backward motion of the wheel will cause said wedge to be pushed along in the 85 shield h', and the inwardly-inclining back or cam h² of said shield will cause the thick end h¹ of said wedge to be wedged between the shield and the teeth of the wheel B², thus arresting further reverse or unwinding motion 90 of the latter.

What I claim as my invention is as follows:

1. In a spring-motor comprising two or more barrels, each having its own shaft and spring, the barrel of one shaft being coupled to the 100 shaft of the adjoining barrel, the combination, with the barrel at that end of the motor oppo-

site to the end where the power of the springs is directly given off, of a winding gear-wheel, substantially as and for the purpose set forth.

2. In a spring-motor comprising two or more barrels, each barrel having its own shaft and spring, and the barrel of one shaft being connected to the shaft of the adjoining barrel, the lower or end barrel formed or provided with gear-teeth, so as to serve as a winding-wheel, substantially as and for the purpose set forth.

3. The combination, with barrel B', formed or provided with gear-teeth, of pinion C on a vertical shaft, *c*, substantially as and for the purpose set forth.

4. In combination with winding-wheel B², 15 the automatic clutch H, comprising a sliding pawl or wedge, *h*, and cam-shield *h'*, substantially as shown and described.

In testimony that I claim the foregoing I have hereunto set my hand this 29th day of 20 October, 1883.

JOHN B. POWELL.
